UNITED STATES PATENT OFFICE.

LAWRENCE W. LUellen, OF MOUNTAIN LAKES, NEW JERSEY, ASSIGNOR TO ROBERT H. DAVIS, OF NEW YORK, N. Y.

GOLF-TEE.

1,152,649.

Specification of Letters Patent.

Patented Sept. 7, 1915.

Application filed March 24, 1915. Serial No. 16,547.

To all whom it may concern:

Be it known that I, LAWRENCE W. LUellen, a citizen of the United States, residing in Mountain Lakes, county of Morris, and 5 State of New Jersey, have invented certain new and useful Improvements in Golf-Tees, of which the following is a specification.

My invention relates to golf tees of a novel character designed to replace the 10 pinch of wet sand which is now commonly used for lifting the golf ball above the surface of the ground before it is hit by the player. I am aware that it has been proposed to use tees made of paper or of rubber for this purpose, but these each have 15 certain disadvantages which has prevented their widespread use.

In accordance with my invention I purpose making the tee of a substantially colorless substance, preferably one which is readily frangible, and also preferably soluble in water. Such a substance is common gelatin. A tee made of this substance in accordance with my invention possesses certain 25 very distinct advantages over the structures of the prior art. It is substantially colorless and therefore becomes practically invisible to the eye of the player when he is in position to hit the ball since the portion of the 30 tee which is not obscured by the ball has no distinctive color to distract the eye of the player from the ball, and the color of the earth or grass will show through the tee. This advantage is not possessed by paper or 35 rubber tees since they are opaque and have a characteristic color of their own different from that of the surrounding grass or earth, and also different from that of the ball so that they tend to lead the player's eye away 40 from the ball when he is about to make a strike. A gelatin tee possesses the further advantage that it is readily frangible so it will be broken into many small bits by the impact of the golf club upon the ball. The 45 fragments of the tee are thus scattered over considerable area and do not litter up the ground in the neighborhood of the point from which the ball is struck, nor do they continue to exist as objects of such size as 50 to impede other players or distract the eye when driving. Another highly desirable property possessed by gelatin is the fact that it is soluble in water so that the small fragments of the tee will immediately dissolve upon the first shower or upon the

ground being sprinkled artificially. There is thus no accumulation of old and battered tees such as occurs when the paper devices are used. Incidentally it is to be noted that the gelatin when dissolved becomes a fertilizer and is a benefit rather than a detriment to the surrounding course. In brief, the advantages possessed by my new structure, therefore, are that it is substantially invisible to the player at the time of driving the ball; will scatter into small bits as the ball is hit, and will dissolve and disappear altogether as soon as the fragments come in contact with water.

In the accompanying drawing, which 70 form a part of this specification, Figure 1 is a side elevation of a golf ball reposing upon one form of my improved tee. Fig. 2 is a transverse sectional view of the device illustrated in Fig. 1. Figs. 3 and 4 are 75 transverse sectional views showing modified forms of the device, and Fig. 5 illustrates a blank from which a tee such as that shown in Fig. 2 may be readily formed.

Referring to the drawings in detail, the 80 numeral 1 designates a hollow, frustoconical tee preferably constructed of gelatin so that it shall be substantially colorless, transparent readily frangible and water soluble. The top 2 is open as shown, forming an annular seat for a golf ball 3. About the lower or larger end of the tee I preferably form a short cylindrical flange 4, which is desirable in that it makes 85 the forming or manufacture of the tee 90 easier.

In Fig. 3 I have shown a somewhat modified form of my device in which there is a head 5, preferably integral with the remainder of the tee. This head is concave 95 with respect to the ball, and is of less radius of curvature than the ball so that while it acts to reinforce the annular seat 2 upon which the ball is supported, and to prevent the distortion of the seat, maintaining its 100 circularity, it does not come into contact with the surface of the ball comprehended within the periphery of the seat 2. If the head 5 were formed with substantially the same curvature as the periphery of the ball, the ball would tend to cling thereto in case either became slightly moist, and, furthermore, even if the ball and the tee remained perfectly dry there would be a tendency for the tee to adhere to the ball owing 105 110

- to the fact that the weight of the ball would cause the somewhat flexible head to cling closely thereto and thus expel the air, forming, in effect, a vacuum cup. Either of 5 these conditions would result in a marked tendency for fragments of the tee to cling to the ball during its flight which, of course, would be fatal to the successful use of the device.
- 10 Fig. 4 illustrates a further modification, which is similar to that shown in Figs. 1 and 2, except that the side wall 6 of the tee is formed upon a curve instead of being frusto-conical.
- 15 It will be readily understood that the forms of tees already described may be molded so that they comprise a single integral, seamless structure. However, in some cases it may be desired to furnish the 20 tee in a flat form, such as the blank 7 shown on a reduced scale in Fig. 5. Owing to the adhesiveness of the gelatin when it is wet the golfer who is provided with such a structure as that shown in Fig. 5 need 25 merely moisten either of the ends 8 and then cause the same to overlap, thereby forming a hollow, frusto-conical device similar to that shown in Figs. 1 and 2, except for the depending flange 4.
- 30 While I have illustrated and described only certain specific embodiments of my device, I appreciate that my invention is susceptible of broad application, and I do not desire to be limited to the precise structure 35 shown and described.
- Having thus described my invention, I claim:
1. A golf tee composed of a water soluble material.
  2. A golf tee composed of a substantially colorless transparent material. 40
  3. A golf tee composed of a readily frangible sheet material.
  4. A gelatin golf tee.
  5. A golf tee composed of a substantially colorless, transparent water soluble material. 45
  6. A golf tee composed of a substantially colorless, transparent readily frangible material. 50
  7. A golf tee composed of a readily frangible, water soluble material.
  8. A golf tee composed of a substantially colorless, transparent readily frangible, water soluble material. 55
  9. A golf tee composed of a substantially frusto-conical base, provided with a reinforcing head having a greater curvature than the curvature of the periphery of a golf ball. 60
  10. A blank for forming golf tees comprising a flat strip of material, adapted to form a frusto-conical surface when its ends are overlapped, said material becoming adhesive when moistened. 65
  11. A golf tee composed of formed sheet material and being substantially frusto-conical in form, the lower base being open and the upper base having a periphery adapted as a seat for a golf ball, said upper base being closed. 70

In witness whereof I have hereunto set my hand in the presence of two subscribing witnesses.

LAWRENCE W. LUELLEN.
